UNITED STATES PATENT OFFICE.

THEODORE BURR, OF BATTLE CREEK, MICHIGAN, ASSIGNOR TO HIMSELF
AND ISAAC C. MOTT, OF SAME PLACE.

IMPROVEMENT IN MACHINES FOR CUTTING FILES.

Specification forming part of Letters Patent No. 40,534, dated November 3, 1863.

To all whom it may concern:

Be it known that I, THEODORE BURR, of Battle Creek, in the county of Calhoun and State of Michigan, have invented a new and useful Improvement in Machines for Cutting Files, Rasps, &c.; and I do hereby declare that the following is a full, clear, and exact description thereof, reference being had to the accompanying drawings, making a part of this specification, in which—

Figures 1 and 2 are right and left side elevations of my improved machine. Fig. 3 is a vertical central section through the machine. Fig. 5 is a front elevation of the same, and Fig. 4 is a perspective view of the chisel used in the machine.

Similar letters of reference indicate corresponding parts in the several figures.

To enable others skilled in the art to make and use my invention, I will proceed to describe its construction and operation.

The two upright sides *a a*, which are suitably strengthened by cross-ties, constitute the frame-work of the machine for containing and supporting the machinery used in supporting, guiding, feeding, and cutting the files.

a' a' are two guide-ways, which incline toward the front part of the machine at any desired angle, and between these ways works a quadrangular block, *b*, which is drilled out to receive the shanks of the chisels used in cutting files. This chisel-stock *b* has a central opening, *c*, through it, which opening is directly above the hole which receives the chisels—*i. e.*, the hole *c* is in the middle of the stock, and the object of this hole is to receive an adjustable spring, which gives force to the stock in its downward stroke, as will be hereinafter described.

The upper end of the chisel-carrying stock *b* carries a loop, *d*, which is acted upon by the cam *e* on the main driving-shaft *e'*, thus giving an alternate rising or lifting movement to the chisel-stock *b* as the arms of the cam act upon the loop. The downward stroke of the chisel-stock is effected by the combined action of a spring, *f*, and the weight of the stock itself. The spring *f* is shown clearly in Fig. 3, and it will be seen that one end of this spring *f* bears upon the stock *b*, entering the hole *c*, while the other end of the spring is rigidly secured to a transverse rock-shaft, *g*,

which carries on one end, outside of the frame *a*, a curved lever-arm, *g'*, by means of which the shaft *g* can be rocked and the pressure of the spring *f* upon the chisel-stock *b* regulated. The lever *g'* has a pin, *h*, projecting from its side and near its outer end, which pin enters one or the other of the depressions *i*, Fig. 2, which are described on the arc of a circle concentric with the axis of the rock-shaft *g*, thus allowing the lever *g'* to be adjusted and set at any desired point, according to the amount of force which it is desired to give the chisel-stock. The lever *g'* is made somewhat elastic, so that it will force the pin *h* against the side *a* of the machine and keep this pin in the position in which it has been set. By this arrangement the force of the downward stroke of the chisel-stock *b* can be increased or diminished at pleasure and while the machine is in operation.

B represents a large rolling-bed, upon which the files are cut. This bed is a cylinder, the axis of which is in a plane with the axis of the stock of the chisel *k*. The shaft of the cylindrical bed *B* carries on one end a large spur-wheel, *j*, and on the other end a large band-wheel, *l*. The latter is intended to give motion to the lower feed-roller, *m*, of the twin rollers *m m'*, and the former engages with a pinion-spur, (not shown,) which is keyed to the shaft *n*, carrying on its end the ratchet-wheel *n'*. This ratchet-wheel is actuated by means of a spring-pawl, *p*, pivoted to a rocking lever, *p'*, which receives its motion from a crank-wheel, *r*, through the medium of pitman *r'*, and the crank-wheel *r* is in turn driven by a pinion, *s*, which receives its motion from a large spur-wheel, *s'*, on the main driving-shaft *e'*. By means of this train of wheel-work, the main shaft *e'* communicates a regular feed-motion to the work which is put between the feed-rollers *m m'* and rests on the cylindrical bed *B*. The main shaft *e'* is in this way made the motor for the tool-stock *b* and for the feed-rollers *m m'* and rolling-bed *B*, which enables me to adapt the strokes of the chisel-stock to movement of the feed-rollers and by these means obtain a harmonious movement of the whole machine.

The adjustment for regulating the amount of feed-motion according to the degree of fineness it is desired to cut the files is obtained

by setting the pitman r' in one or the other of the holes in the lever p' , and, by this shortening or lengthening the vibration of this lever p' , the feed can be regulated to a nicety. The driving feed roller m , which receives its motion from the band-wheel l , supports the outer end of the file-blank, and the upper roller, m' , is acted upon by rubber or other springs t t , in its bearings, which keep the file-blank down on the feed-roller m , and also upon the rolling-bed B . It will be seen, by reference to Fig. 3, that the spring-roller presses upon the blank at a point which is between the feed-roller m and the rolling-bed, thus keeping the blank in its place and pressing it equally upon both rollers m and B' , and as the chisel k strikes perpendicularly to the axis of this rolling-bed B there will be no tendency of the chisel to slip the blank in either direction in the operation of producing the file-surface on the blanks.

In cutting files which have one rounded surface, triangular files, &c., a groove, v , is formed around the rolling bed or cylinder B to receive the rounded or angular surfaces and to keep the blanks in a steady, fixed position to receive the edge of the chisel properly; and in cutting files with inclined surfaces I employ a chisel which is pivoted to its stock, as shown clearly in Fig. 4. By thus pivoting the chisel-point k to its stock k' , it will be seen that the cutting-edge will adapt itself to inclinations from a horizontal plane, and should the blanks (of square or flat files) from any cause become disarranged while being cut, the chisel k will still make the ridges or abrasions uniform from one side to the other of the file, whereas, if the chisel-point was rigidly fixed to its stock or shank, it would only cut in a plane parallel with the surface of the rolling-cylinder B , and in many cases the cuts or furrows made in the file-blanks would be deeper at one side of the file than at the other.

The advantages of the rolling-bed B , upon which the files are cut, over the flat bed hitherto used, are as follows: Most files are made tapering from end to end—*i. e.*, they are thinner and narrower at the ends than at the middle, producing what is called “bellied files.” It is therefore necessary, in cutting the file-surface on such blanks, to be very careful that the entire surface of the blank, as it is fed under the chisel, is properly sustained upon its bed. Otherwise the blow of the chisel will break or so bend the blank as to render it useless. In machine for cutting files having flat beds this difficulty frequently occurs. In my machine, with a rolling or cylindrical bed B and a pressure-roller, m' , for keeping the blank down on its bed, and yielding to

accommodate itself to the varying thickness of the blank, as above mentioned, the blanks, of whatever size, thickness, or degree of taper, will be supported upon a firm bed which is unvarying in its character and which supports the blank at a point directly under the edge of the inclined chisel. Then, to compensate for the varying thinness or taper of the blank or the hardness of the metal thereof, and to regulate the force of the stroke of the chisel to this condition of the blanks, the spring-lever g' is used, which projects sufficiently far toward the front of the machine to be controlled by the operator, who can, by simply raising or depressing this lever, increase or diminish the force of the stroke of the chisel upon the blank, and this can be done without stopping the machine.

I do not claim, broadly, the use of feed-rollers in a file-machine, unless such rollers constitute the bed which supports the file-blank and sustains the percussive force of a chisel, which is arranged to operate upon the broad surfaces of the file-blank, substantially as herein described, as I am aware that rollers acting simply as feed-rollers in a machine for nicking the edges of blanks have been used, and are shown in the Patent of Milton Whipple, dated April 1, 1862. Neither do I claim the rocking-chisel. Neither do I claim, broadly, a spring made adjustable for regulating the force of the chisel.

Having thus described my invention, what I claim as new, and desire to secure by Letters Patent, is—

1. A file-cutting machine constructed with inclined ways a' a' , inclined chisel-stock b , adjustable power-spring f , and a rotating bed, B , all arranged substantially as described.
2. In a file-cutting machine, the combination of a rotary bed, B , feed-roller m , and spring-pressure roller m' , and inclined cutter-stock b , substantially as described.
3. Arranging the spring-pressure roller m at an intermediate point between the rolling-bed B and the feed-roller m , substantially as described.
4. Cutting or producing the abraded surface upon the broad sides of files upon a cylindrical rotating bed, substantially as described.
5. The combination and arrangement, with the system of mechanism which actuates the chisel and the roller-bed, of the roller-bed, the inclined chisel, and the spring-regulating device, all constructed and operating substantially as described.

THEODORE BURR.
